UNITED STATES PATENT OFFICE

153,989

DESIGN FOR A DOLLY FOR TRANSPORTING AIRPLANES AND THE LIKE

Mahlon C. Snyder, Hamburg, N. Y.

Application May 8, 1947, Serial No. 138,902
Term of patent 14 years

(Cl. D14—3)

To all whom it may concern:

Be it known that I, Mahlon C. Snyder, a citizen of the United States, residing at Hamburg, in the county of Erie and State of New York, have invented a new, original, and ornamental Design for a Dolly for Transporting Airplanes and the like, of which the following is a specification, reference being had to the accompanying drawing, forming part thereof.

In this drawing:

Fig. 1 is a front elevation of a dolly for transporting airplanes and the like, showing my new design.

Fig. 2 is a top plan view of the same.

Fig. 3 is a side elevation of the same.

Fig. 4 is a perspective view of the same.

I claim:

The ornamental design for a dolly for transporting airplanes and the like, as shown.

MAHLON C. SNYDER.
